United States Patent Office.

EDWARD O. SCHWAGERL, OF ST. LOUIS, MISSOURI, ASSIGNOR TO HIMSELF AND SHICKLE, HARRISON & CO., OF SAME PLACE.

Design No. 4,675, dated February 21, 1871.

DESIGN FOR A PARK-SEAT.

The Schedule referred to in these Letters Patent and making part of the same.

I, EDWARD O. SCHWAGERL, of St. Louis, in the county of St. Louis and State of Missouri, have invented a certain new, useful, and ornamental Design for a Park-Bench or Seat, which is shown in the accompanying drawing, in which—

A is an end frame;
a are lugs cast thereon; and
B are the seat and back slats, secured to the frame by means of screws, bolts, or rivets C, which pass through the lugs a.

The end frames are preferably made of cast-iron and imitate a rustic frame made of unbarked branches of trees.

I claim—

The design for a park-bench or seat, substantially as above set forth.

EDWARD O. SCHWAGERL.
